LINK BAND FOR ORNAMENTAL AND USEFUL PURPOSES

Robert Einsele, Pforzheim, Germany, assignor
to Friedrich Doppenschmitt, Pforzheim, Germany

Application February 12, 1936, Serial No. 63,546
In Germany February 23, 1935

6 Claims. (Cl. 63—3)

This invention relates to a link band of flat links arranged side by side.

It is known to arrange side by side plate-shaped links on wire plaiting or on woven strips of wire by means of turned over edges engaging over the edges of the carrier strip so that they form a closed harness over the one side and over the edges of the carrier band.

Such band body which is employed for the manufacturing of bracelets, especially wristlets for watches, but also of waist-belts, neck bands and ankle bands, possesses the inconvenience that the armouring produced by the plate-links loses its closeness if, in the course of time, lengthening of the carrier band occurs by continuous use. The total tensile stress of the band must be taken up by the strip of wire fabric or plaited wire-work and it happens thus that, besides the lengthening, tearing of the carrier band from the edge may occur as another inconvenience of the band body.

The inconveniences are overcome by the invention.

The novelty consists in that the flat links, arranged side by side on the carrier strip, are connected with one another not only by the strip but also by other means.

In this manner the tensile stress is distributed on two elements, i. e. the carrying band and the chain-like body formed by the connected flat links, so that lengthening or even tearing of the carrying band is absolutely prevented.

Several embodiments of the invention are illustrated by way of example in the accompanying drawing in which:—

Fig. 1 shows in top plan view a portion of a link band according to the first first form of construction.

Fig. 2 is a rear elevation of Fig. 1.

Fig. 3 is a section on line 3—3 of Fig. 2.

Fig. 4 is a section along the middle line of Fig. 2.

A second embodiment of the invention is shown in

Fig. 5 in section along the middle line and in Figs. 6, 7 and 8 which are cross sections of the band showing different forms of the bottom.

Fig. 9 shows in elevation a punched piece for a flat band link.

The carrying band *a* consists of a strip of wire fabric or plaited wire work produced in known manner by hand or by a machine. Milanese plaiting is preferably employed on account of its pliability and flexibility. The flat links *b* arranged side by side on the carrying band *a* have

each one a slot *c* through which two connection elements *d* engage and effect the connection of the links *b*.

The connecting element *d* has two hooks *e* (Fig. 4) or *e*₁ (Fig. 5), hooked into the slots *c* of two adjacent links *b*. The hooks *e* are completely rolled inwards so that the end edge of each hook bears against the inner side of the corresponding connecting element *d* and grip over the corresponding web *f* of the flat link *b*. In order that the complete rolling in of the hooks *e* up to contact with the inner side of the connecting elements *d* can be carried through, the flat links *b* have cut out portions *g* through which the ends of the hooks engage (Fig. 4). Such a connection of the links *b* is very solid and can be exposed to strong tensile stresses.

The hooks *e*₁ (Fig. 5) abut at their ends, and as they are not rolled in completely, cutting out of the links *b* at *g* is not necessary.

The flat links *b* connected in the manner described or in any other suitable manner, are held on the carrying band *a* by folded over or rolled over ends *h*. As shown in Figs. 3 and 8 the end *i* is sunk in the carrying band *a* by flat pressing in, whereas the end *h* shown in Fig. 6 is pressed into the carrying band *a* as the end is rolled in like a claw. The end edge *i* may, however, rest upon the carrying band *a* as shown in Fig. 7 or be bevelled and rounded.

As shown in Figs. 3, 6 and 7 a shoulder *k* corresponding to the thickness of the connecting elements *d* is formed on the visible surface of the band body by the provision of the connecting elements *d*. This shoulder will disappear more or less, if, as shown in Fig. 8, the flat links *b* have a slight outwardly directed moulding *m*.

In order to prevent the band borders *h* from impeding the pliability and flexibility of the band body, if their lateral edges *n* strike against each other during the bending of the band body, they are tapered towards the edges *i* (Fig. 9).

The invention is evidently not limited to the embodiments illustrated. It comprises any forms of construction which utilize the inventive idea. Hereto belongs, for instance, a band body in which the flat links *b* have, instead of one slot, several transverse slots side by side, and in which consequently two flat links *b* are joined by means of several connecting elements *d*.

The carrier band *a* instead of being made of wire fabric or wire work, may be made of any other suitable pliable and flexible material, such as leather, cloth, blade spring material and the like.

I claim:—

1. A link band for ornamental and useful purposes, especially for bracelets and wristlets for watches, which consists of a band strip of pliable and flexible material, such as wire fabric and wire plaiting, flat links the ends of which grip over the side edges of said band strip, said links having each a slot, and of elements for additionally connecting said links, said elements having hook-shaped ends hooked into said slots of said links, the edges of said hook-shaped ends joining on the rear side of said flat links between this rear side and said band strip.
2. A link band for ornamental and useful purposes, especially for bracelets and wristlets for watches, which consists of a band strip of pliable and flexible material, such as wire fabric and wire plaiting, flat links the ends of which grip over the side edges of said band strip, said links having each a slot, and of elements for additionally connecting said links, said elements having rolled up ends engaging through said slots of said flat links and bearing almost against the inner surface of their own element.
3. A link band for ornamental and useful purposes, especially for bracelets and wristlets for watches, which consists of a band strip of wire fabric and wire plaiting, of flat links the ends of which grip over the edges of said band strip and are tapered and sunk in the band strip, said flat links having slots, and of means for additionally connecting the flat links and having hook-shaped ends hooked into said slots of said flat links and joining on the rear side of said flat links between this rear side and said band strip.
4. A link band for ornamental and useful purposes, especially for bracelets and wristlets for watches, which consists of a band strip of wire fabric and wire plaiting, of flat links the ends of which grip over the edges of said band strip and are tapered and sunk in the band strip and having slots, and links connecting said flat links and having hook-shaped ends rolled in so that, engaging through said slots of said flat links, they almost touch the inner side of their own connecting links.
5. A link band for ornamental and useful purposes, especially for bracelets and wristlets for watches, which consists of a band strip of pliable and flexible material, such as wire fabric and wire plaiting, flat links the ends of which are tapered and grip over the side edges of said band strip, said links having each a slot, and of elements for additionally connecting said links, said elements having hook-shaped ends hooked into said slots of said links, the edges of said hook-shaped ends joining on the rear side of said flat links between this rear side and said band strip.
6. A link band for ornamental and useful purposes, especially for bracelets and wristlets for watches, which consists of a band strip of pliable and flexible material, such as wire fabric and wire plaiting, flat links the ends of which are tapered and grip over the side edges of said band strip, said links having each a slot, and of elements for additionally connecting said links said elements having rolled up ends engaging through said slots of said flat links and bearing almost against the inner surface of their own element.

ROBERT EINSELE.
